DESIGN FOR A HAMPER

Vincent Giambone and Charles L. Abate, Brooklyn, N. Y.; said Giambone assignor to Charles Giacalone, Brooklyn, N. Y.

Application September 21, 1946, Serial No. 133,488

Term of patent 7 years

(Cl. D58—4)

To all whom it may concern:

Be it known that we, Vincent Giambone and Charles L. Abate, both citizens of the United States, both residing at Brooklyn, New York, in the county of Kings and State of New York, have invented a new, original, and ornamental Design for a Hamper, of which the following is a specification, reference being had to the accompanying drawing, forming a part thereof.

In the drawing:

Fig. 1 is a front perspective view of a hamper, showing my new design;

Fig. 2 is a front elevational view;

Fig. 3 is a top plan view; and

Fig. 4 is a rear perspective view of the same.

We claim:

The ornamental design for a hamper, as shown.

VINCENT GIAMBONE.
CHARLES L. ABATE.
